PRODUCTION OF VALUABLE PRODUCTS BY
CONVERSION OF CARBONACEOUS MATERIALS

Rudolf Wietzel and Bruno Engel, Ludwigshafen-on-the-Rhine, Germany, assignors to I. G. Farbenindustrie Aktiengesellschaft, Frankfort-on-the-Main, Germany, a corporation of Germany

Application August 26, 1929, Serial No. 388,612
In Germany June 1, 1927

8 Claims. (Cl. 196—52)

The subject-matter of this application is a continuation-in-part of the subject matter of our copending application Ser. No. 280,114 filed May 23rd 1928, now Patent No. 1,925,551, for an invention relating to the production of valuable products, such as hydrocarbons and oils from carbonaceous materials.

The present invention relates to the recovery of valuable hydrocarbons and oils from mixtures thereof with solid substances, and to the production of the said hydrocarbons and oils from carbonaceous materials.

We have found that such hydrocarbons and oils may be recovered with particular advantage from mixtures thereof with solid substances, in particular from the crude solid or pasty products obtained by low temperature carbonization, cracking and extraction of carbonaceous materials, and in the destructive hydrogenation of coals, tars, mineral oils and the like, and which consists of mixtures of oils and other valuable hydrocarbons with soil substances such as carbonaceous residues ash constituents, or other solid admixtures such as catalysts, by stirring the mixture, preferably at a slightly elevated temperature, with a liquid in which the oil is insoluble, or only slightly soluble, and to which an alkaline reaction has been imparted and which contains small amounts of a wetting or emulsifying agent, such as sulphonated aromatic or aliphatic hydrocarbons, in particular nucleoalkylated sulphonated acids of aromatic hydrocarbons, cellulose pitch, saturated or unsaturated fatty acids, their salts and derivatives, glue, saponines, dextrine, oxidation products of paraffins, and the like. Products obtained by sulphonating products of the destructive hydrogenation of coal, tars and the like are also suitable.

When the adhesion between the solid substances and the oils has been sufficiently loosened, the oil is separated in various ways, as for example mechanically, as by centrifugal means, preferably in the warm, or by means of electric or magnetic fields, or in other suitable ways, or by the application of several methods of separation simultaneously.

The process may be applied alone or in combination with other methods, such as subsequent low temperature carbonization, or extraction and the like; and the mixtures may also be subjected to repeated treatment and to the action of different kinds of liquids. The conditions in respect of pressure and temperature

may be varied within wide limits according to the character of the substances under treatment.

Materials suitable for treatment comprise, for example, the residues from the distillation of tar, cracking residues, crude mineral oils, the residues from the extraction of coal and the like, or the residues obtained in the heat treatment under pressure, with or without hydrogen, of coals, peat, cellulose, tar, oils, bitumen or other carbonaceous substances.

It has also been found suitable, in treating the oleaginous sludge, to employ solutions which also contain salts such as chlorides, sulphates and the like. If the concentration of these be such that the specific gravity of the solutions is equal to, or greater than that of the solids to be separated, it is easy to carry on the operations, for instance the centrifuging, continuously.

In centrifuging especially, there is no need to stir up the sludge under treatment with the added liquid beforehand in a special stage of the process, but the material under treatment and the added liquid may be introduced simultaneously into the separator, such as a centrifuge. This not only saves one working stage, but also, in certain circumstances, leads to a better separation of the oil and solid residue. The rate of separation of the material on the one hand, and the added liquid on the other, depends on the character of the former.

The amount of emulsifying and wetting agents to be added is usually very small, for example 0.05 per cent or sometimes still less. The optimum quantity depends on the character of the material under treatment in each case. The other working conditions, such as temperature, speed of the centrifuge and the like, also depend on the material under treatment and on the wetting agent used, and must be determined by experiment in each case. For example, in centrifuging a coal sludge, such as is obtained, for example, in the extraction of coal with solvents under pressure, it is preferable to work at a temperature not exceeding 100° to 110° C. when an equal quantity of an 0.05—0.1 per cent aqueous solution, for example of alkylated naphthalene sulphonated acids, is added to the sludge during the centrifuging process.

The added liquid after being freed from oil by centrifuging may be used over again.

The employment of the said substances adapted to reduce the surface tension, especially the emulsifying and wetting agents, for example, the organic substances, which contain the rad-

icle of a mineral acid in the molecule, such as aromatic and aliphatic sulphonic acids, their derivatives, and substitution products, is not restricted to the separation of oils from mixtures with solid substances, but also offers great advantages in carrying out the destructive hydrogenation, cracking and extraction under pressure of species of coal, tars, mineral oils and other carbonaceous products, or several of these processes combined, since excellent yields of valuable, and especially liquid hydrocarbons are obtained.

These processes are hereinafter referred to for the sake of brevity as the production of valuable products by heat treatment of carbonaceous materials. The liquid employed in this case need not necessarily be rendered alkaline, although in some cases, this may be advantageous.

This process is especially adapted for the extraction of any kind of coal, under pressure, with liquid organic solvents, comprising a great variety of substances (especially those of high boiling point range), and particularly fractions or transformation products of mineral oils or tars, such as cresols, xylene, naphthalene, anthracene oil, hydrogenation products of naphthalene or benzene, or mixtures of benzene and alcohol or halogenated hydrocarbons and the like.

The process may also be employed with advantage in the destructive hydrogenation, and also in cracking, since the said additions exert a splitting action on the hydrocarbons and the like.

The operation may be conducted under high pressures, such as 200 atmospheres, and when required, with special addition of hydrogen or other gases, and also at pressures as low as about 50 atmospheres, in which event the excess pressure generated under certain conditions by the liberation of gases from the coal, is released.

If the operation be carried on in the presence of hydrogen, a portion of the coaly substance passing into solution is hydrogenated, especially at temperatures above 400° C.

In addition to the substances added to reduce the surface tension of the resulting liquid products, other inorganic or organic substances, such as alkalies, zinc oxide, magnesia and the like, may also be added.

A suitable apparatus for carrying out my process is shown in the accompanying drawing to which are applied sufficient legends of suitable character to render further description thereof unnecessary.

The following examples will further illustrate the nature of the said invention which, however, is not restricted thereto. The parts where not otherwise stated, are by weight.

Example 1

Brown-coal is stirred up with tetrahydronaphthalene, with an addition of 0.05 per cent of sodium isopropylnaphthalene sulphonate, and heated to 350° C. under pressure. The coal is transformed into products soluble in benzene, which amount to about 75 to 80 per cent of the initial substance free from ash and water. The insoluble residue consists of undissolved coal and ash. Without the use of the wetting agent, the yield is considerably lower.

Example 2

100 parts of crude mineral oil, containing 4 per cent of constituents boiling up to 180° C., are heated with 5 parts of benzenesulphonic acid. 22.5 parts of a mixture of crude hydrocarbons boiling up to 180° C., are distilled over.

Example 3

100 parts of a brown-coal producer tar, containing no constituents boiling below 220° C., are heated in the presence of 5 parts of phenol borate, 35 parts of a mixture of hydrocarbons, boiling up to 220° C being distilled over.

Example 4

Brown coal (lignite) is treated similarly as described in Example 1 but at a temperature of between 460 to 470° C. and in the presence of hydrogen at a pressure of 200 atmospheres. About 60 percent or more of the brown coal are then converted in part into liquid and also in part into solid hydrocarbons, such as paraffin wax which after separation from the undecomposed coal may be converted in known manner into benzine. If an emulsifying agent be not employed, only about 40 to 50 percent of the initial material are converted into the aforesaid hydrocarbons.

We claim:

1. In a process for splitting high boiling hydrocarbons into lower boiling hydrocarbons without the addition thereto of substantial quantities of water, the step of adding to the hydrocarbons to be split an organic emulsifying and wetting agent capable of reducing the surface tension of the products resulting from the splitting and selected from the group consisting of aromatic and aliphatic sulphonic acids and their alkali metal salts, cellulose pitch, saturated and unsaturated fatty acids, their salts and derivatives, glue, saponins, dextrine and oxidation products of paraffins.

2. The process according to the preceding claim in which the wetting agent employed is an alkylated aromatic sulphonic acid.

3. The process according to claim 1 in which the wetting agent employed is sodium iso-propyl naphthalene sulphonate.

4. The process according to claim 1 in which the wetting agent employed is benzene sulphonic acid.

5. In the cracking of high boiling hydrocarbons to lower boiling hydrocarbons without the addition thereto of substantial quantities of water, the step of adding to the initial material to be cracked an organic emulsifying and wetting agent capable of reducing the surface tension of the products resulting from the cracking and selected from the group consisting of aromatic and aliphatic sulphonic acids and their alkali metal salts, cellulose pitch, saturated and unsaturated fatty acids, their salts and derivatives, glue, saponins, dextrine and oxidation products of paraffins.

6. In the destructive hydrogenation of high boiling hydrocarbons to lower boiling hydrocarbons without the addition of substantial quantities of water, the step of adding to the initial material to be destructively hydrogenated an organic emulsifying and wetting agent capable of reducing the surface tension of the products resulting from the destructive hydrogenation

and selected from the group consisting of aromatic and aliphatic sulphonic acids and their alkali metal salts, cellulose pitch, saturated and unsaturated fatty acids, their salts and derivatives, glue, saponins, dextrine and oxidation products of paraffins.

5. The process according to the preceding

claim in which the wetting agent employed is an alkylated aromatic sulphonic acid.

6. The process according to claim 6 in which the wetting agent employed is sodium iso-propyl naphthalene sulphonate.

RUDOLF WIETZEL.
